UNITED STATES PATENT OFFICE.

WILLIAM A. JAMESON, OF NIAGARA FALLS, NEW YORK.

DESIGN FOR A SPOON.

SPECIFICATION forming part of Design No. 30,649, dated May 2, 1899.

Application filed March 27, 1899. Serial No. 710,710. Term of patent 7 years.

To all whom it may concern:

Be it known that I, WILLIAM A. JAMESON, a citizen of the United States, residing at Niagara Falls, in the county of Niagara, State of New York, have invented and produced a new and original Design for Spoons, of which the following is a specification, reference being had to the accompanying drawings, showing a part thereof.

10 Figure 1 is a plan or elevation view of the front or obverse side of a spoon, the whole of which embodies my design. Fig. 2 is a similar view of the reverse or rear side of the spoon, and Fig. 3 is a cross-section on line $a-a$ of Fig. 1.

15 The leading feature of my design consists in the long straight twisted central portion of the shank A, containing four spiral concave

grooves $b-b-b-b$ or corrugations of equal size, said portion of the shank connecting the short, 20 curved, and plain portion a' of the shank terminating in the round bowl B with the plain, flattened, and elongated pear-shaped end C of the handle, having a smooth rounded edge. The bowl has a circular edge d , as shown, and 25 shaped similar to a ladle.

The design for the reverse side of the spoon is substantially the same as that of the obverse side.

What I claim is—

30 The design for a spoon or similar article herein shown and described.

WILLIAM A. JAMESON. [L. S.]
